(57) CLAIM

The ornamental design for a food container lid, as shown and described.

DESCRIPTION

FIG. 1 is a perspective view of a food container lid of our design;

FIG. 2 is a front view of the food container lid of FIG. 1;
FIG. 3 is a right side view of the food container lid of FIG. 1;
FIG. 4 is a back view of the food container lid of FIG. 1;
FIG. 5 is a left side view of the food container lid of FIG. 1;
FIG. 6 is a top view of the food container lid of FIG. 1; and,
FIG. 7 is a bottom view of the food container lid of FIG. 1.
The broken lines shown in the Figures are included for the purpose of illustrating features in the lid, that form no part of the claimed design.
